UNITED STATES PATENT OFFICE.

PAUL A. DELSING, OF SEATTLE, WASHINGTON.

FIREPLACE-DAMPER.

1,078,189.

Specification of Letters Patent. Patented Nov. 11, 1913.

Application filed May 5, 1913. Serial No. 765,703.

To all whom it may concern:

Be it known that I, PAUL A. DELSING, a citizen of the United States, and resident of the city of Seattle, county of King, and State of Washington, have invented certain new and useful Improvements in Fireplace-Dampers, of which the following is a specification.

My invention relates to fire place dampers and comprises certain novel features which will be hereinafter described and particularly pointed out in the claims.

The object of my invention is to produce a fire place damper having features of simplicity, cheapness of cost, ease of adjustment, strength and durability, and of superiority in other lines, which will give it material advantages over fire place dampers as generally constructed.

In the accompanying drawings I have shown my invention embodied in the form which is now most preferred by me.

Figure 1 shows the damper, complete, ready for installation, but separate from the fire place, the view being a perspective taken from a direction to show the inner side of the damper, or that which faces toward the back of the fire place. Figs. 2 and 3 are transverse sectional elevations, Fig. 2 showing the damper in closed position while Fig. 3 shows the damper as partly raised.

The manner of making this damper, is to mount it upon a length of angle iron, or other suitable shape, which forms the foundation or frame member for the damper and also the supporting beam for the fire place lintel. The damper, so mounted, is a self-contained structure which may be assembled in the shops and requires but little labor to put it in place. It is however, evident that the foundation plate or frame might, if made slightly shorter, be applied to a fire place after it has been built.

The frame member herein shown consists of the angle bar 2, which is made of such length as to span the fire place opening and rest upon the walls at each side, and is of such weight as will enable it to properly support the masonry imposed thereon. The web 20 of this beam is the one upon which the brick of the fire place lintel is placed, the web 21 extending upward close against the inner surface of the front wall. The pivot bearings for the damper are mounted upon the upper edge of this inner, vertical

web 21, the means shown for mounting the damper consisting of two pairs of bars 5 and 50, secured to the web 21, so as to come even with the ends of the damper. The rearmost bar 50, has its upper end bent back, or toward the rear, so as to form, with the other bar 5, an upwardly opening yoke for the reception of the pivot journals 11 of the damper.

The damper plate 1, is made of a size to fit the throat of the fire place and, preferably, has a flange 10 turned up on its swinging edge, to thereby strengthen it and assist in preventing warping. At each end and as close as feasible to the outer or front edge of the damper, pivot journals 11 are secured, these being shown as consisting of round pins secured to the damper by passing through holes formed in ears or lugs 12, formed by cutting the end of the plate and turning a section thereof upward.

The damper has an operating arm 3, secured thereto at about the middle of its length and extending downward until its lower end is accessible from without the fire place. I have shown it as extending slightly below the lintel, where it may be engaged by the foot, or any convenient tool, to throw the damper backward and upward, the extent of this movement depending upon the vigor of the kick, or the distance which it is pushed back. This operating arm should be made of substantial construction, so that it will not become bent out of shape by use. I have shown it as made of a substantial bar of iron bent into the form of a bracket, of which one arm, 31, is secured to and extends transversely of the damper, thus forming a reinforcement for the damper plate, and the other arm, 30, extends downward and forms the operating bar proper. The operating bar 3 is further strengthened by a brace bar, 32, which connects the parts 30 and 31. The lower arm 30, is provided with a horizontally and transversely extending surface, adapted to be engaged by the teeth of a holding bar 4, by which it is held in adjusted position. This is preferably done by providing the arm 30, with a slot for the reception of the holding bar 4, which also serves to securely hold these two members in proper relation. The holding bar 4 is pivoted at the under edge of the lintel and extends a short distance outward, or toward the front of the fire place, and, if necessary, downward, to be readily accessible for dis-

engagement of the teeth thereof from the arm 30 by pressure applied from outside. Its inner end is provided with a hook, 42, or in other way is prevented from disengagement from the arm 30.

Whether the damper drops down to the closed position, or stops in a partly raised position, will depend upon how quickly the bar 4 is released after being raised. It is possible, by giving the bar only a quick touch, to drop the damper one notch or tooth at a time. The operating arm being at the center of the length of the damper, all effort applied thereto is balanced and no warping strains are produced, nor is there any tendency to throw the damper out of its bearings.

What I claim as my invention is;

1. A fire place damper comprising a damper plate having pivot bearing members substantially in line with one side edge, complementary bearing members secured to the outer wall of the throat and above the lintel level, a controlling arm secured to the damper plate centrally of its length and extending downward to below the lintel level, a holding bar pivoted beneath the lintel and having a short end extending outward from its pivot for operative engagement and having a longer toothed end extending backward from its pivot and with its toothed edge engaging by gravity the controlling arm of the damper plate.

2. In a fire place damper, in combination, a lintel-supporting bar, pivot bearing members secured to said lintel-supporting bar and extending upward back of the lintel to locate their bearings well above the lintel and next

the outer wall of the throat, a damper plate having pivots on one edge fitting within said bearings, a controlling bar secured to said damper plate centrally of its length and extending downward to a point below the lintel, the lower end of said controlling bar being slit, and a holding bar pivoted at the under edge of the lintel and extending through the slot in the controlling bar, the under edge of said holding bar being toothed to engage and hold the controlling bar when the same is pushed back.

3. In a fire place damper, in combination, a lintel-supporting bar of angle cross section having one flange extending upward along the inner wall of the arch, the said bar being of a length to extend beyond the sides of the fire place opening, pivot bearing members secured to said bar with their bearings well above the lintel and at the lateral edges of the fire place throat, a damper plate having end pivots in line with one side edge and adapted to be carried by said pivot bearing members, a controlling bar extending downwardly from the pivot edge of the damper plate and centrally of its length, a locking or holding bar pivoted upon the lintel-supporting bar and having a toothed edge engaging by gravity the controlling bar to hold it in adjusted position.

In testimony whereof I have hereunto affixed my signature this 28th day of April, 1913.

PAUL A. DELSING.
